UNITED STATES PATENT OFFICE.

WILLIAM F. HELMOND, OF HARTFORD, CONNECTICUT, ASSIGNEE TO
UNDERWOOD TYPEWRITER COMPANY, OF NEW YORK, N. Y., A
CORPORATION OF NEW JERSEY.

TYPE-WRITING MACHINE.

No. 821,036.

Specification of Letters Patent.

Patented May 22, 1906.

Application filed July 18, 1905. Serial No. 270,299.

To all whom it may concern:

Be it known that I, WILLIAM F. HELMOND, a citizen of the United States, residing in Hartford, in the county of Hartford and State of Connecticut, have invented certain new and useful Improvements in Type-Writing Machines, of which the following is a specification.

This invention relates to the letter-feeding mechanism of type-writing machines, and particularly to the device which checks the escapement-wheel against undue backward rotation when the carriage-rack is released therefrom.

The object of the invention is to prevent wear upon the teeth of the escapement-wheel, such as occurs in machines in which said teeth force the check out of their way, and to provide against faulty operation of the mechanism.

I provide, in addition to the usual feeding-dogs, a back-check, which is caused to reciprocate simultaneously with the feeding-dogs into and out of the escapement-teeth, said back-check being operated by the finger-keys instead of by the teeth of the escapement-wheel, thus reducing somewhat the amount of power required to drive the carriage and making a more certain operation of the back-check. I also provide the check with a pivot, so that in case during rapid operation of the machine the check should engage the wrong tooth of the escapement-wheel the latter will vibrate the check out of the way.

In the accompanying drawings, Figure 1 is a perspective view of the escapement mechanism of the well-known "Underwood" type-writing machine, showing my improvements applied thereto. Fig. 2 is a rear elevation of the same.

The carriage 1 of the Underwood machine is spring-propelled by means of a strap 2 and provided with a rack 3, which meshes with a pinion 4, the rack being releasable from the pinion in order to enable the carriage to run quickly forward. Connected to the pinion is an escapement-wheel or curved rack 5. Upon a rocker 6 are mounted spacing and detent dogs 7 and 8, which move transversely of the escapement-wheel 5 and alternately into and out of the notches therein to let the escapement-wheel and carriage advance step by step under the influence of the spring

mechanism 2. An abutment 9, carried upon a table or frame 10, which reciprocates backward and forward at each key-stroke, engages the rocker 6 to vibrate the same in one direction, while a spring 11 returns the frame 10 to normal position. A spring 12 is also provided for the escapement-dogs. At its rear end the frame 10 is provided with arms 13 14, whereby it is pivotally mounted upon the upper ends of a pair of upright rock-arms 15 16, connected by a rock-shaft 17, hung upon pivots 18. When a key is depressed, the frame 10 moves back, together with the arms 13 14 and the rock-arms 15 16, as well as the dog-rocker 6, and when the key is relieved from pressure all of said parts move forward to normal position. As so far described the parts are in common use in said Underwood type-writing machine.

Upon the upright rock-arm 16 I fix an arm 19, having a diagonal extension 20, directed up toward the escapement-wheel 5. Upon the free end of the extension 20 I pivot at 21 a back-check pawl 22, which normally stands between adjoining teeth 23 of the escapement-wheel 5 to prevent undue backlash of the latter whenever the rack is released from the pinion 4. The arm 20 being fixed to the rock-arm 16 vibrates backwardly, together with the frame 10 and the dog-rocker 6, whereby the back-check 22 is carried sideways out of the path of the teeth 23 of the escapement-wheel, thus avoiding the necessity of being forced out by the action of said escapement-teeth themselves and avoiding wear upon said escapement-teeth. Upon the relief of the key from pressure the parts all return to normal position, together with the arm 20 and the back-check 22, the latter never needing to be touched by the escapement-teeth.

When the machine is operated at high speed, and particularly if the escapement-dogs 7 8 are not adjusted with precisionness relatively to one another, there is some liability of the back-check 22 colliding with the wheel-tooth from which it has just escaped, this collision being liable to take place during the return or forward movement of the rock-arm 16 and 20 to normal position; but in such event no harm results, because the back-check is so pivoted that the escapement-tooth 23 will simply turn it upon the pivot and pass

by. This vibration of the back-check is illustrated in dotted lines at Fig. 2. A weighted arm 24, formed upon the back-check, will restore the same to normal condition as soon as the escapement-tooth 23 passes. A stop 25 upon the arm 24 catches over the top edge of the arm 20 to arrest the downward movement of 24, while a similar stop 26 engages the under edge of the arm 20 to limit the upward vibration of arm 24.

Having thus described my invention, I claim—

1. In a type-writer letter-feeding mechanism, the combination with a carriage, a series of escapement-teeth, and feeding-dogs coöperating therewith, of a back-check pawl connected to reciprocate simultaneously with the feeding-dogs into and out of the series of escapement-teeth, said pawl pivoted and adapted to yield when engaged by the escapement-teeth in advancing and thereby forced out of their path.
2. In a type-writer letter-feeding mechanism, the combination with a carriage, a series of escapement-teeth, and feeding-dogs coöperating therewith, of a back-check pawl connected to reciprocate simultaneously with the feeding-dogs into and out of the series of escapement-teeth, said pawl pivoted and adapted to yield when engaged by the escapement-teeth in advancing and thereby forced out of their path; means being provided for

restoring the back-check pawl to normal position after such action by the escapement-teeth.

3. In a type-writer letter-feeding mechanism, the combination with a carriage, a series of escapement-teeth and feeding-dogs coöperating therewith, of an arm vibrating transversely of the series of escapement-teeth at the feeding operation, a back-check pawl pivoted upon said arm and adapted to yield when engaged by the escapement-teeth in advancing and thereby forced out of their path, and means restoring said pawl to normal condition.

4. In a type-writer letter-feeding mechanism, the combination with a series of escapement-teeth and feeding-dogs coöperating therewith, of an arm vibrating transversely of the series of escapement-teeth at the feeding operation, a back-check pawl pivoted upon said arm and adapted to yield when engaged by the escapement-teeth in advancing and thereby forced out of their path; said back-check pawl having a gravity-arm for restoring it to normal condition, and stops being provided for limiting the vibration of said back-check pawl upon its pivot.

WILLIAM F. HELMOND.
